DESIGN FOR A CONTAINER

Chester R. Underwood, Jackson, Miss., assignor to The Knox Glass Bottle Company, Jackson,
Miss., a corporation

Application November 26, 1934, Serial No. 54,155

Term of patent 7 years

To all whom it may concern:

Be it known that I, Chester R. Underwood, a citizen of the United States, residing at Jackson, in the county of Hinds and State of Mississippi, have invented a new, original, and ornamental Design for a Container, of which the following is a specification, reference being had to the accompanying drawing, forming a part hereof.

I claim:

The ornamental design for a container, substantially as shown.

CHESTER R. UNDERWOOD.
